CLAIM

We claim the ornamental design for a container and a blank for forming the container, as shown and described.

DESCRIPTION

FIG. 1 is a perspective view of a container in a closed position, embodying our new design, as viewed from above showing the top, rear and a side of the container.

FIG. 2 is front elevation view of the container of FIG. 1.

FIG. 3 is a top plan view of the container of FIG. 1.

FIG. 4 is a side elevation view of the container of FIG. 1, the opposite side being a mirror image thereof.

FIG. 5 is a rear elevation view of the container of FIG. 1; and,

FIG. 6 is a bottom plan view of the container of FIG. 1.

The long dash-short dash-long dash lines in the drawings represent fold lines. The dashed lines in the drawings are for illustrative purposes only and form no part of the claimed design.
